DESIGN FOR AN ARTIFICIAL BAIT CASTING PLUG

Wayne G. Levan, Reading, Pa.

Application August 21, 1946, Serial No. 132,710

Term of patent 14 years

(Cl. D31—4)

To all whom it may concern:

Be it known that I, Wayne G. Levan, a citizen of the United States of America, residing at Reading, in the county of Berks and State of Pennsylvania, have invented a new, original, and ornamental Design for an Artificial Bait Casting Plug, of which the following is a specification, reference being had to the accompanying drawings, forming part thereof.

Figure 1 is a top plan view of an artificial bait casting plug embodying my new design.

Fig. 2 is a side elevational view, the opposite side being the same.

Fig. 3 is a bottom plan view, with one of the hooks omitted.

Fig. 4 is a front elevational view, and

Fig. 5 is a rear elevational view, with the rear hook omitted.

I claim:

The ornamental design for an artificial bait casting plug, as shown.

WAYNE G. LEVAN.
